COMBINED THERMOMETER AND SUPPORT

H. Brainard Brown, Rochester, N. Y., assignor to
 Taylor Instrument Companies, Rochester, N. Y.,
 a corporation of New York

Application June 5, 1934, Serial No. 729,106

2 Claims. (Cl. 73—52)

This invention relates to a thermometer and more particularly to a combined thermometer and support.

For many purposes, especially in a refrigerator, it is desirable to suspend a thermometer from a shelf made of spaced bars or rods. In the past, it has been the practice to provide a thermometer designed for such use, with a single hook for suspension from a bar or rod of the refrigerator shelf. However, a thermometer suspended in this manner is not securely held in position and consequently is easily dislodged and broken.

In accordance with the main feature of the present invention, it is proposed to provide the thermometer with a hanger having spaced resilient arms terminating in hooks to engage the spaced bars or rods of a shelf.

This and other features of the invention will appear from the detailed description and claims when taken with the drawing in which Fig. 1 is a front elevation of a combined thermometer and support of the present invention; Fig. 2 is a side elevation of the combined thermometer and support of Fig. 1 with the thermometer also indicated in dotted lines in a different position of adjustment; and Fig. 3 is a view of the hanger or support detached from the thermometer.

Referring to the drawing, 5 designates a thermometer of any well-known construction, but as herein shown, it is provided with a metal scale plate 6 having side flanges 7. These flanges at a point above the center of gravity of the thermometer, are provided with an integral ear 8 which ears serve as a mounting for a hanger or support 9 of the thermometer. The hanger 9 is pivoted on these ears by means of hollow rivets 10 so that the thermometer can be moved to various positions about a longitudinal axis. This hanger is preferably made of a somewhat resilient strip of metal and is provided with spaced arms 11 and 12 terminating, respectively,

in hooks 13 and 14 formed by bending the end portions of the strip back upon itself until these hooks extend in a direction generally parallel to the arms 11 and 12. It will be noted that the hooks 13 and 14 are provided, respectively, with a rounded portion 15 and 16 adapted to grip round bars of small cross-section, while the hooks proper are adapted to engage shelf bars R of relatively large rectangular cross-section. 5

When using the combined thermometer and support, the hanger 9 is sprung until the hooks 13 and 14 pass between the adjacent bars or rods of a shelf. Thereafter the natural resilience of the arms 11 and 12 causes these hooks to engage the mentioned rods or bars. Since there is a pivotal connection 10 between the hanger or support 9 and thermometer 5, the thermometer may be moved to various positions of adjustment best suited to easy reading, of which one position is indicated in full lines and another in broken lines. It will be appreciated that owing to the friction existing between the ears 8 of the thermometer and the arms 11 and 12 of the support, the thermometer is frictionally held in the position to which it is adjusted. 25

The present disclosure is given by way of illustration and the invention is not to be limited thereby, except as specifically defined in the following claims.

I claim:

1. In combination, a thermometer including a backing plate provided with side flanges, and a U-shaped hanger formed of resilient material and mounted on said side flanges, the free ends of said hanger terminating in spaced hooks. 30

2. In combination, a thermometer including a backing plate provided with rearwardly projecting ears, a U-shaped hanger having its arms pivoted on said ears, the free ends of said arms having integral hooks. 35

H. BRAINARD BROWN.
